N. Y.

PACKING FOR FRAGILE ARTICLES.

Original application filed April 15, 1922, Serial No. 553,139. Divided and this application filed July 17, 1922. Serial No. 575,516.

To all whom it may concern:

Be it known that we, MORRIS KOPPELMAN and SIMON COOPER, citizens of the United States, and residents of the borough of Brooklyn, in the county of Kings, city and State of New York, have invented certain new and useful Improvements in Packings for Fragile Articles, of which the following is a specification.

10 The improvements relate to packing units for fragile articles, such as eggs, electric light bulbs, and other globular objects made of glass or other brittle material, and have for their object, among others, the production 15 of a packing unit of highly efficient form in such a manner and of such materials that the strength, durability, and usefulness of the unit are increased and the cost of production decreased. The present application 20 is a division and continuation of our application filed April 15, 1922, Serial No. 553,139, as far as the subject-matter of the same corresponds.

Heretofore it has been proposed to make 25 packing units having holders projecting from a sheet or "flat," by taking a sheet of straw-board, heavy paper or the like, and stamping or rolling it so as to produce the projecting holders, but so far as we are informed 30 none of these proposed devices has ever been extensively used, and none of them has proved to be of any practical or commercial value. One reason for this is that even if the paper or board is thoroughly saturated 35 with water or other liquid, and then formed by flat dies or rolls, or otherwise, the fibres having once been set—in the original making—in certain positions and relations will always have a tendency to return 40 thereto, and to deform the unit and the parts thereof, and to reduce its strength to such an extent that it will not do its work properly. Another reason is found in the fact that in forming the projecting members 45 from such a sheet of material the area is necessarily very greatly increased, and the fibres stretched and torn, even where openings are made in the material and the displacement of the opening utilized in forming the projections. The result is that the 50 holders are weak and badly formed and will not hold their shape or resist the shocks and strains of use. If board of sufficient thickness were used to permit the formation of

holders thereon without rupturing or unduly weakening the material, the objection first noted would still be present, and the weight of the board and its cost would be prohibitive. Other reasons which account for the fact that these prior devices have never gone into use are found in the shape and proportions of the holding projections which give them a tendency to yield under ordinary strains and permit the eggs or other articles to become loose in their cells, and even permit the cells to move thereon and displace the eggs or cause them to break, through indirect contact with each other on opposite sides of cell walls or holders or otherwise.

The present invention is in the nature of a modification or improvement of the egg packing described and shown in United States Letters Patent No. 1,413,047, of April 18, 1922, to Morris Koppelman, and another, in which conical projections similar to those herein shown are set forth, which packing may also be made of pulp, as therein stated.

In practicing the present improvements upstanding holders of substantially conical form are formed in the sheet or flat simultaneously with the formation of said sheet, as set forth in the said patent, the formation of the sheets and the projecting holders being preferably accomplished by one and the same process or series of operations, and these holders have a web or cup-like connecting and reinforcing portion extending over the space circumscribed by the edges of their upper openings, the pitch or inclination of the outer walls of the holders being in the opposite direction to that of its inner walls, which, with the bottom portion, form the cup-like interior. In forming these parts wood pulp or cellulose or other loose fibrous material is employed, the fibres being first placed in a liquid bath. Macerated paper, thoroughly disintegrated and mixed with water until it has the consistency of a thick soup may be employed, as may other similar materials. The formation of the parts may then be made by felting, as described in the said co-pending application. If desired, and particularly where the nature of the fibre employed makes it advisable, a hardening substance, such as Portland cement may be added to the bath in quantity sufficient to

secure the desired result, but this is not necessary or even preferable in most cases.

We are aware that packing members of this general type have heretofore been described in United States Letters Patent, and that in such patents it has been proposed to form such holders by means of a pulp sucking process, but the holders properly have not been of the upstanding type and have not been capable of performing the functions and securing the advantages of the present holders. The advantages are apparent. The holders are of such form and are so constructed and arranged as to hold the eggs or other articles securely and to lock the cell walls or "fillers" against all lateral movement, while at the same time they are only relatively rigid and will have a sufficient degree of elasticity to accommodate themselves to slight variations in the sizes of the eggs or other articles without cracking or checking them, or permitting such injury under the most severe shocks and strains of shipment and handling. Moreover the nature of the construction insures proper and accurate form and the preservation of that form in use, since any pressure on the unit or any part thereof will tend to move its fibres from their normal position and will be constantly resisted thereby, to the end that the parts will always have a tendency to return to their original form, which causes them to exert a counter pressure when slightly pressed or drawn therefrom and to hold the articles in a firm but only relatively rigid grip.

The usefulness of the device in preventing breakage of eggs and other articles in packing, shipping and handling and for other purposes will be apparent. In addition to these advantages however the construction permits the inspection of the eggs without removing them from the flats on which they are mounted and the exhibition of them in stores and elsewhere on the said flats. When the cell-forming fillers are removed from the flat the eggs will remain in position on their holders, and a flat—usually supporting thirty-six eggs—may be taken out of a case or crate without disturbing the eggs thereon, and restored thereto after inspection or exhibition. This is largely due to the fact that the holders are preformed so that the flat and its holders thereon maintain their form, even after the innumerable shocks and vibrations of a long railroad journey, cartage and handling.

The improvements are illustrated in the accompanying drawings, referred to herein, in which Figure 1 is a vertical medial section of a portion of two of the packing units with fillers of standard form between them and eggs positioned in the holders, and Fig. 2 is a plan thereof.

The holding and packing units consist of sheets of material 2 with raised cone frustum-like members 1 thereon, arranged in parallel rows. Each sheet will usually have six rows of six holders each, making thirty-six holders in all, this being the standard capacity of ordinary sheets or "flats" and the cell forming members or fillers between them. The portions of the sheets between the projecting holders are curved upwardly to a slight extent or grooved as shown at 8, where they receive the edges of the filler 3, so that when a sheet is placed on the top of a filler it will engage the upper edges of the filler members in these grooves and thereby provide a means for further positioning and holding the two parts. The lower edges of the filler are securely held between the projecting holders. Each holder consists of an upwardly and inwardly inclined ring 4 and a downwardly and inwardly inclined interior wall 5 with an approximately horizontal bottom and central portion 6, the angles and arrangement of these members may be varied to some extent, but it is important that the opening at the top shall be large enough to receive either end of the egg or other article to be placed therein, so the edges of the opening will engage the wall of the article at such an angle that there will be a degree of wedging action. The depressed central portion of the holder extends to a point above the sheet proper 2, which is the base of the holder, so that normally it does not come in contact with the article positioned therein, except at its upper part. If however pressure is exerted in forcing the article therein so that the holder is spread to some extent no harm will be done, and the holder will grip the article because of the tendency of the holder to return to its normal shape due to the fact that the fibres of which it is composed have been brought together and permitted to set and dry in substantially normal positions, that is to say without being distorted to any material extent by force or any other influence. Nevertheless the holders will serve their purpose, perhaps less efficiently, if the cup-like inside portion and the mouth or aperture are made large enough to permit the bottom of the article to rest normally upon the bottom of the cup, without wedging. It has been found that where the holders are thus formed they have greater strength, and will preserve their shape under all ordinary conditions of use. The bottom portion 6 is preferably slightly concavo-convex, but this is not absolutely essential, nor is its exact position. These may be varied according to the nature of the article, and the use to which the packing is put. In the drawing eggs 7 are shown, and it will be observed that they rest upon the lower holders above their bottoms and

have their upper ends immediately below the bottom portions 6 of the holders above, which may receive other eggs or be employed as a cushion between the top or bottom 5 layer and the walls of the case or package. Usually ten layers of eggs formed in the manner shown are placed in one case, making 360 in all. The packing unit therefore serves to hold the eggs or other articles 10 above and below it, so that but one flat or unit is used for each layer of eggs, except where additional units are used at top and bottom as cushions. If desired the holders may be made lower, and the middle portion 15 6 permitted to project below the base sheet so that each egg will be within the upper and lower edges of its cell or compartment, and will at the same time be separated from those above and below it and held. Nor is 20 the construction limited to one in which the upper end of the egg is held by the middle bottom portion of the holder above it.

An important advantage of the construction herein set forth is that any number of 25 sheets may be superposed one upon another, with the holders telescoped, so that a nested relation is obtained, greatly reducing the space occupied by a certain number of fillers when they are stored or shipped empty.

30 While the manufacture of the holders in the manner herein described and of the substances mentioned secures a peculiar and advantageous result, it must be understood that the improvements are not limited to any particular method of manufacture or composition, so far as they relate to the form and arrangement. The form of each holder is substantially an arch, of which the egg or other globular article therein forms the key- 35 stone so that great strength and durability and resistance to shocks and jars is obtained, and the tendency of these strains to deform and break down the holder is resisted. This would not be the case if the holders were so 40 formed that they would give way and spread or bend. The cuplike concave portion spanning the opening at the top of each holder also forms in effect a reverse arch to resist strains tending to crush the holder or cause 45 it to give way; and the fact that the bottom portion of the cup-like member is normally out of contact with the globular article positioned in its upper edges is important to the 50 performance of this function though not essential. The inclined sides of the holders diverging from one another form in effect deep channels or grooves, with wide mouths and narrow bottoms, so that when the fillers are placed thereon they will be guided to the 55 bottom thereby and to a position in which their lower edges are confined in a relatively narrow space, so as to lock them in position and prevent lateral movement. In the drawings these fillers are shown as of rectangular 60 form, but it is obvious that they may have 65

any other suitable form so long as they fit the holders. The holders also, instead of being arranged with the centers of adjacent rows opposite each other may be arranged in staggered or other relation, and the fillers 70 modified accordingly.

What we claim is:

1. A packing for eggs and other fragile globular articles, comprising a sheet having thereon a series of projecting holders each 75 consisting of a round upstanding rim of substantially truncated conical form, an inwardly and downwardly inclined interior part extending to a point near the base of the said upstanding portion, and a central bottom portion, the downward inclination of the said inner portion being approximately tangential to the curve of the article to be placed therein, the space defined by the edge formed by the junction of the upstanding 80 portion and the interior portion being of lesser diameter than the greatest diameter of said article and adapted to hold the latter by contact therewith between its middle and its bottom and the bottom part of the holder 85 being normally below the said bottom of the article.

2. A packing for eggs and other fragile globular articles, comprising a sheet having thereon a series of projecting holders each 95 consisting of a round upstanding rim of substantially truncated conical form, an inwardly and downwardly inclined interior part extending to a point near the base of the said upstanding portion, and a central 100 bottom portion, the downward inclination of the said inner portion being approximately tangential to the curve of the article to be placed therein, the space defined by the edge formed by the junction of the upstanding portion and the interior portion being of lesser diameter than the greatest diameter of said article and adapted to hold the latter by contact therewith between its middle and its bottom and the bottom part of the holder 105 being normally below the said bottom of the article, but above the bottom surface of the sheet.

3. A packing for eggs and other fragile globular articles, comprising a sheet having 115 thereon a series of projecting holders each consisting of a round upstanding rim of substantially truncated conical form, an inwardly and downwardly inclined interior part extending to a point near the base of the 120 said upstanding portion, and a central bottom portion, the downward inclination of the said inner portion being approximately tangential to the curve of the article to be placed therein, the space defined by the edge 125 formed by the junction of the upstanding portion and the interior portion being of lesser diameter than the greatest diameter of said article and adapted to hold the latter by contact therewith between its middle and 130

its bottom and the bottom part of the holder being normally below the said bottom of the article, vertically arranged spacing and supporting members having their lower edges 5 between the said holders and extending above the same and to the upper part of said article and forming compartments therefor, another sheet of similar construction to the first named sheet resting on and supported 10 by the said spacing and supporting members with the bottom portions of its holders above the tops of the articles in the lower holders and its holders extending upwardly to receive other articles or act as a cushion or 15 packing.

4. A packing for eggs and other fragile globular articles, comprising a sheet having thereon a series of projecting holders each consisting of a round upstanding rim of substantially truncated conical form, an inwardly and downwardly inclined interior part extending to a point near the base of the said upstanding portion, and a central bottom portion, the downward inclination 25 of the said inner portion being approximately tangential to the curve of the article to be placed therein, the space defined by the edge formed by the junction of the upstanding portion and the interior portion being 30 of lesser diameter than the greatest diameter of said article and adapted to hold the latter by contact therewith between its middle and its bottom and the bottom part of the holder being normally below the said 35 bottom of the article, the said sheet and its said holders being pre-formed in the shape described by fibres brought together and lying upon one another in normal positions.

5. A packing unit for eggs and other fragile globular articles consisting of a sheet having upstanding relatively rigid holders for such articles thereon, each holder consisting of a circular ring-like device with upwardly and inwardly inclined outer walls 45 and downwardly and inwardly inclined inner walls, and a laterally disposed portion at the bottom thereof, said unit being adapted to be superposed on other similar units and to have other similar units superposed thereon with the holders telescoped so that a plurality of the said units may be nested.

6. A packing unit for eggs and other fragile globular articles consisting of a sheet 55 having upstanding relatively rigid holders for such articles thereon, each holder consisting of a circular ring-like device with upwardly and inwardly inclined outer walls and downwardly and inwardly inclined inner walls, and a laterally disposed portion at the bottom thereof, said unit being formed of free fibres superposed and assembled in the form described in normal positions.

7. A packing for eggs and other globular

articles, comprising a sheet having thereon 65 a series of raised members for receiving and holding the said articles, said raised members being spaced apart and arranged in rows, and the sheet having convex portions extending parallel with said rows and between them.

8. A packing for eggs and other globular articles, comprising a sheet of fibrous material having thereon a series of raised holders, each holder comprising an outer annular 75 wall extending upwardly and inwardly from the sheet, an interior portion extending inwardly and downwardly from its upper edges and spanning the aperture bounded by said upper edges, said outer wall being relatively rigid, and said inner portion forming a relatively deep cup or inverted dome connecting the said upper edges and reinforcing them against spreading strains, as when a globular article is forced in between said edges, the construction and relation of the parts being such that the said article may be pressed in between the said edges so as to wedge therein without pressing against the lower part of the said inner 90 portion.

9. The combination of upright compartment forming members, and flat members at the top and bottom of said upright members and normally in contact therewith, said 95 flat members having relatively rigid holders projecting into compartments, each of said holders being pre-formed with an aperture at its upper part and a cup-like member inside it of a size to receive the end portion 100 of the egg or other article without material expansion or compression when the compartment forming members and flat members are in normal position.

10. The process of packing eggs and other 105 globular articles, which consists in placing the said articles in individual cup-like holders mounted on a flat member, each cup-like holder having a recess of a size to receive the end portion of one of said articles and support it vertically and laterally, placing upright compartment forming members comprising intersecting strips of material over said holders, so that the strips enter between them and each article is received 110 by a compartment and the compartment forming members are held in position by the said holders, then placing another member consisting of similar holders and flat member on the said cell-forming members to 120 close the cells at the top, without materially compressing or expanding the first mentioned holders.

Witness our hands this 12th day of July, 1922, at the city of New York, in the county 125 and State of New York.

MORRIS KOPPELMAN.
SIMON COOPER.
